UNITED STATES PATENT OFFICE.

JOHN C. SCHELLENG, OF EAST ORANGE, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed November 24, 1922. Serial No. 602,949.

To all whom it may concern:

Be it known that I, JOHN C. SCHELLENG, a citizen of the United States, residing at East Orange, in the county of Essex, State 5 of New Jersey, have invented certain new and useful Improvements in Signaling Systems, of which the following is a full, clear, concise, and exact description.

This invention relates to signaling systems and particularly to apparatus for use 10 in connection with the control of signaling circuits such as telegraph circuits.

It is an object of the present invention to cause, in response to signaling impulses, the 15 operation of a pair of electron discharge devices having their input electrodes oppositely connected to a signaling path and adjusted in a manner such that for predetermined charges on the input electrodes different current changes are produced in the 20 output circuit thereby causing the differential effect of such current changes.

In accordance with the above and other objects, there is provided a pair of vacuum 25 tubes of the three-element type having their input circuits connected oppositely to a signaling path. In each of the input circuits, there is connected a resistance of several megohms, whereby with the charge on 30 the control electrode of the tubes normally positive and tubes adjusted to normally work on the point of the grid voltage and output current characteristic having the greatest curvature, the resistance of the grid filament circuit of the one tube becomes small while the resistance of the grid filament circuit of the other tube becomes very large. With such an arrangement, with a 35 corresponding change in the voltage, a high degree of efficiency in the detection of signals. Each of the tubes has its output circuit connected to a common signaling path in which a current responsive device is connected, such current responsive device being 40 supplied with a unidirectional current impulse irrespective of the polarity of the impulses received on the input circuit of the 45 combination.

In the drawing, Fig. 1 illustrates diagrammatically one embodiment of the invention. Fig. 2 shows a modification of the

arrangement shown in Fig. 1. Fig. 3 is a curve characteristic of one of the tubes with output current plotted against grid voltage.

In Fig. 1, a receiving antenna 4 is connected serially with a coil 5. This coil 5 serves to impress signals on coil 6. Coil 6 is connected in the grid filament circuits of a pair of three-element vacuum tubes 7 and 8 connected in a manner whereby the tubes 65 have their input electrodes associated with the signaling path in push-pull relation. The term "push-pull," as used in the present instance, refers to an arrangement of vacuum tubes in which their input or grid electrodes are associated with the signaling path oppositely. One end of the coil 6 is directly connected with the grid electrode 9 of tube 8, while the other end thereof is connected to the grid electrode 10 of tube 7. 75 A condenser 13 is connected across the terminals of the coil 6 to increase the selectivity of the system. Also connected across the terminals of the coil 6 and between the grid electrodes 9 and 10, and having a terminal connected with filaments 11 and 12 of tubes 7 and 8 respectively, are a pair of resistances 14 and 15. The value of each of these resistances is approximately several megohms whereby the resistance of the 80 grid filament circuits of the two tubes is controlled by the character of the impulses impressed on the respective grid electrodes as, for example, when the grid electrode 10 is made positive with respect to the filament 90 11, only a small portion of the current flows through the resistance 14, the greater portion thereof flowing between the grid 10 and the filament 11 and then through the resistance 15. At the same time grid 9 of tube 95 8 becomes at least as negative as the cathode, and the internal impedance of the tube 9 becomes substantially infinite.

In the output circuits of the tubes 7 and 8 which extend between the plate electrodes 100 16 and 17 and the filaments 11 and 12 is a battery 18 and a telephone receiver 19. A condenser 20 may be shunted around the receiver 19.

The arrangement just described may be 105 employed for detecting different kinds of signaling impulses as, for example, damped wave trains or voice or signal modulated continuous trains of waves. In the case of damped wave trains, each train of waves 110

changes the normal charge on the grid electrodes which, in the preferred form of the invention, is made normally positive. The waves thus received are impressed on the control electrodes of each of the tubes. Thus, when a wave is impressed on coil 6, which produces a voltage in the direction of the solid arrow, the grid electrode 10 of tube 7 is made more positive, while 10 grid electrode 9 of tube 8 is made less positive or negative with respect to the cathode. The result of this will be an increase in the electrons flowing between cathode 11 and plate 16, while the opposite effect is 15 produced in tube 8, that is, the space current in this tube is decreased. The decrease in the current of tube 8 is greater than the increase in tube 7 due to two effects, one that the voltage change on the more negative grid 9 is greater due to the greater impedance on which it is derived, and the other that the tubes may be operated on a curved portion of the natural characteristic of the tubes. The circuit of such current 20 may be traced from the upper terminal of coil 6 to the point in which the resistance 14 and the grid electrode 10 are connected. Owing to the value of this resistance, only a very small portion of the current flows 25 therethrough, the greater portion of the current flowing between the grid 10 and cathode 11, the resistance 15 and the turns of coil 6 to the point from which the circuit was traced.

28 Now if an impulse is impressed on the coil 6 causing a voltage in the direction of the dotted arrow, a result opposite to that just described is produced as, for example, the space current through tube 8 increases 30 while that through tube 7 decreases in accordance with the condition just described. The current in the output circuit including the receiver 19 is varied but will be in the same direction irrespective of the character 35 of the impulses impressed on coil 6.

The primary purpose of the connection of resistances 14 and 15 in the grid filament circuits of tubes 7 and 8 is to secure the maximum detecting action. In other words, 40 it is desired to obtain the maximum change in the output circuit due to a received signal impulse, that is, a change in the charge on the grid electrodes oppositely of the two tubes produces a net change in the output circuit equal to the algebraic sum of the changes in the two tubes.

45 In Fig. 3, curve A represents the plate curve characteristic of one of the tubes and is obtained by plotting grid voltage against plate current, while curve B represents the grid current curve characteristic with the addition of the current flow through the input resistance when the grid of such tube is made positive. The line drawn below the axis and designated as "C" represents the

current flow through the resistance connected in bridge of the input circuit of the tube, the grid of which becomes negatively charged for such condition.

For example, suppose a voltage E is impressed between the grids of tubes 7 and 8, the components of this voltage when the tubes 7 and 8 are made positive and negative respectively, are E_1 and E_2 , as shown by the curve of Fig. 3. For this condition, a current equal to D flows in the input circuit of tube 7 while the current through the resistance 15 of tube 8 is of an equal value D' since the space current is zero when the grid of tube 8 is negative. By applying the voltage E to the output current curve characteristic A, it is seen that the current in tube 7, due to voltage E_1 , is of a value equal to b while for the tube 8, the current is equal to c . The current change in tube 7 being positive and that in tube 8 being negative, the rectification effect of the tube combination is equal to the algebraic sum of these two current changes. Curves B and C are plotted assuming that the normal grid voltage is zero or negligibly positive. Either one of these curves gives the current in the pair of wires crossing broken line FF (Fig. 1), a current to the right being considered positive and one to the left negative. It is seen that to the right of line FF the current may have one or more branches depending upon whether current may flow from grid to filament, that is, whether the grid of the tube considered is positive or negative with respect to its filament. In the former case the curve lies to the right of the origin and is the sum of two parts, first, the grid current, a rapidly rising line concave upward, and second, that through the shunt resistance this being a straight line through the origin; in the latter case the line lies to the left of the origin because of the negative potential and below the line because the direction of the current also is reversed. The latter line is straight because when the current is negative no current flows to it; the current across FF is, therefore, only that through the shunt resistance. Since the total current obtained by taking the algebraic sum of two currents across line FF must be zero, the current at g is opposite that at h . This condition being true, the grid potentials resulting from applications of E must be such as to give these equal currents which in the diagram (Fig. 3) are D and D' . It is now also obvious from the diagrams that to do this the grid potentials of the two tubes must be opposite in sign and unequal in magnitude. The oppositeness of sign leads to oppositeness of change of plate current. The inequality of magnitude leads directly to inequality in plate current which leads to rectification in this circuit. It is evident from the straight-

ness of curve characteristic A in region *bc*, that there would be no rectification due to any curvature which A might possess, while as shown, very appreciable rectification may 5 be present in the grid voltage thus leading to a resultant change in the total plate current. It is evident from curve A that the rectification effect is greater as described than it would be from a circuit which depended for rectification on the curvature of 10 curve A.

In the modification shown in Fig. 2, like parts are represented by the same reference characteristics with the prime indices added.

15 A pair of vacuum tubes of the three-element type 7' and 8' have their grid electrodes connected with conductors 34 and 35, respectively, which extend from a distant station at which transmitting apparatus, such as 20 the key 36, for transmitting impulses in accordance with a desired message, is located. To produce the same results obtained in connection with the arrangement shown in Fig. 1, the input circuit of each of the tubes is 25 bridged by a resistance of several megohms.

Connected in the output circuit of the tubes 7' and 8' is a polarized relay 25 comprising a soft iron magnetic core 26 having a pair of pole pieces 27 and 28. Surrounding these pole pieces are magnetizing windings 29 and 30. These magnetizing windings, are connected serially with the output circuit of the vacuum tubes 7' and 8'. Pivoted to the core 26 is an armature 31 which 35 is adapted to swing between pole pieces 27 and 28 and cooperates with a pair of oppositely disposed contacts. Attached to the free end of the armature 31 is a spring 32 which serves to bias the armature 31 in its 40 normal position. With such an arrangement, a relay is provided which has three positions, that is, the armature may be in engagement with either of its contacts or in the central or neutral position, as determined by the character of the received 45 impulse and the spring 32. The line conductors 34 and 35 have serially connected therewith an operating winding 33 which encircles the armature 31 and serves to magnetize the armature so that it may be attracted by either pole piece 27 or 28, depending upon the polarity of the impulse traversing this winding.

With the arrangement shown in the drawing, space current normally flows through the tubes 7' and 8' which would cause a corresponding flow of current through the magnetizing windings 29 and 30. To compensate for this current flow whereby the current through the magnetizing windings 29 and 30 is reduced substantially to zero during the non-reception of signals, the magnetizing windings have connected in bridge thereof an inductance 38, an adjustable resistance 39 and a battery 40. This

combination of elements composes an arrangement whereby the effect of the normal space current in the tubes 7' and 8' may be balanced thereby reducing the polarizing current, through the relay 25, to a small 70 value.

When the key 36 is operated to connect the positive terminal of battery 37 with the line conductor 34, an impulse of a positive character flows over the line conductor 34 and 75 charges the grid electrode 10' of tube 7' more positively and also in its continued flow passes through operating winding 33 of relay 25. The making of the grid electrode 10' of tube 7' more positive with respect to 80 the filament electrode 11' increases the space current through this tube in a manner similar to that disclosed in connection with Fig. 1. Also, the grid electrode 9' of tube 8' for the condition selected is made more negative 85 with respect to the filament electrode 12', whereby the current in this tube decreases, thus causing a corresponding change in the current in the output circuit of the tube combination. The introduction of the resistances 14' and 15' in the input circuits of these tubes produces an effect in which the impedance of the grid filament circuit of the tubes 7' is made relatively small, while the impedance of the grid filament circuit of the tube 8' is made comparatively large. The current flowing through the magnetizing windings 29 and 30 is thereupon increased, the effect of which, together with the current of a positive polarity which 90 flows through the winding 33, armature 31 is moved to engage the upper contact.

Should the key 36 be operated in a manner to connect the negative pole of battery 37 with the conductor 34, a condition opposite 105 to that just described will exist.

It is to be noted, however, in the two conditions selected, the current in the output circuit of the tubes 7' and 8' is in the same direction, that is, the direction of the current 110 in the output circuit of the tubes 7' and 8' is in the same direction irrespective of the character of the impulse impressed on the line conductors 34 and 35 which causes the operation of the tubes 7' and 8' in a manner similar to that described in connection with Fig. 1.

When current is allowed to flow through the magnetizing windings 29 and 30, the armature 31 will swing toward the pole piece 27 when a positive impulse is impressed on the line conductors, and will swing in the opposite direction when a negative impulse is transmitted.

The invention claimed is:

1. A signaling system comprising a signaling path, a pair of electron discharge devices associated with said signaling path, each of said devices having a cathode, an anode and a control electrode, means for 125

- maintaining said control electrode at least as positive as the cathode electrode such that the devices are working near a point of maximum rectification, and a path to which 5 input potentials are to be applied connecting said cathode and control electrodes including shunt resistances of a value sufficient to produce different voltage drops across the respective tubes for a given signal 10 pulse.
2. A signaling system comprising a signaling path, a pair of electron discharge devices associated with said signaling path, each of said devices having a cathode, an 15 anode and a control electrode, means for maintaining said control electrodes at least as positive as the cathode electrodes thereof that the devices are working near a point of maximum rectification, a path to 20 which input potentials are to be applied connecting said cathode and control electrodes including shunt resistances of a value sufficient to produce different voltage drops across the respective tubes for a given signal 25 impulse, and means in the output circuit responsive to the differential current effect therein due to said different voltages.
3. A signaling system comprising a signaling path, a pair of vacuum tubes having cathode, anode and grid electrodes with the grid electrodes connected oppositely to said signaling paths, a branch common to the anode electrodes of said tubes, means for normally maintaining said grid electrodes 35 at least as positive as the cathode electrodes thereof such that the devices are working near a point of maximum rectification, a path to which input potentials are to be applied including shunt resistances of several 40 megohms, whereby different voltage drops across the respective tubes is produced for a given signal impulse, and means in the common branch of the output circuit responsive to such differential effect.
4. In combination, a source of positive and negative impulses, a pair of vacuum tubes responsive to impulses transmitted from said source, each of said tubes having a cathode, an anode and a grid electrode, means for maintaining said grid electrodes 50 normally positive, whereby current normally flows in the output circuit of said tubes, a relay connected in the output circuit of said tubes comprising operating and magnetizing windings, said magnetizing windings being included in the output circuit of said tubes, and means associated with said relay and tubes for reducing the current in said output circuit during non-signaling periods 55 substantially to zero.
5. In combination, a source of electric impulses of opposite polarity, a pair of three-element electron discharge devices having their input electrodes connected oppositely 60 in series with each other across said source, an output circuit having a common branch, means for causing said tubes to work on the portion of the input voltage and output current characteristic of the greatest curvature and whereby different voltage drops are produced across the respective tubes, and a polarized relay having its magnetizing windings connected in the common branch of 65 said output circuit in which unidirectional impulses are repeated.
6. In combination, a source of electric impulses of opposite polarity, a pair of vacuum tubes having cathode, anode and grid electrodes, the grid electrodes being oppositely connected in series with each other 70 across said source, means for charging said grid electrodes whereby space current normally flows in the tubes during non-signaling intervals, an output circuit, and means whereby different voltage drops are produced across the respective tubes to cause the differential effect of current changes due to said different voltages to be applied to 75 said output circuit.
7. In combination, a source of electric impulses of opposite polarity, a pair of vacuum tubes having cathode, anode and grid electrodes, the grid electrodes being oppositely connected in series with each other 80 across said source, an output circuit having a common branch and a path to which such impulses are to be applied connecting said cathode and grid electrodes including shunt resistances of such value to produce different 85 voltage drops across the respective tubes 90 for a given signal impulse to cause the differential current effects to be applied to said common branch due to said different voltages.
8. In combination, a source of electric impulses of opposite polarity, a pair of vacuum tubes having cathode, anode and grid electrodes, the grid electrodes being oppositely connected in series with each other 95 across said source, means for normally charging said grid electrodes whereby current flows therethrough during non-signaling intervals, an output circuit having a common branch, a polarized relay responsive to the operation of said vacuum tubes 100 having operating and magnetizing windings, said magnetizing windings being included in the common branch of said output circuit, and means whereby different voltage 105 drops are produced across said tubes for a given signal impulse to cause the differential effects to be applied to the magnetizing windings of said relay due to said different voltages.
- In witness whereof, I hereunto subscribe my name this 22nd day of November A. D., 1922.
- JOHN C. SCHELLENG.
